UNITED STATES PATENT OFFICE.

GEORGE D. SAILER, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A WATER-COOLER.

47,474.

Specification for Design.

Patented June 15, 1915.

Application filed April 17, 1915. Serial No. 22,183. Term of patent 14 years.

To all whom it may concern:

Be it known that I, GEORGE D. SAILER, a citizen of the United States, and residing at Jeannette, in the county of Westmoreland, State of Pennsylvania, have invented a new, original, and ornamental Design for a Water-Cooler, of which the following is a specification, reference being had to the accompanying drawing, forming part thereof.

The figure is a perspective view of a water cooler, showing my new design.

I claim:

The ornamental design for water cooler, as shown.

GEORGE D. SAILER.
